UNITED STATES PATENT OFFICE.

ARTHUR RYDER, OF HARTFORD, NORTHWICH, ENGLAND.

FLUID-PRESSURE-ENGINE INDICATING APPARATUS AND THE LIKE.

1,289,923.

Specification of Letters Patent.

Patented Dec. 31, 1918.

Application filed June 6, 1917. Serial No. 173,232.

To all whom it may concern:

Be it known that I, ARTHUR RYDER, subject of the King of Great Britain, residing at Hartford, Northwich, in the county of Chester, in the Kingdom of England, have invented certain new and useful Improvements in and Relating to Fluid-Pressure-Engine Indicating Apparatus and the like, of which the following is a specification.

10 The present invention relates to improvements in indicating arrangements for fluid pressure engines.

An object of the present invention is to provide an indicating arrangement combined with a fluid pressure engine so that an indicated diagram can be obtained at any moment desired without stopping the engine, and on the other hand, the apparatus normally is isolated from the engine.

20 The invention is more particularly described with reference to the accompanying drawings, in which:—

Figure 1 is a diagrammatic view of the arrangement.

25 Fig. 2 is a front elevation of part of the apparatus.

Fig. 3 is a corresponding plan view; and Figs. 4 and 5 are modified arrangements.

Fig. 6 is a sectional elevation of a plug.

30 Fig. 7 is an outside side view.

On the crank shaft 1 of the engine or on a shaft driven thereby at equal speed, are keyed in correct phase with the pistons of the fluid pressure engine the power of which 35 is to be indicated, eccentric disks 2. These disks act as operative members to move the indicator element in synchronism with the reciprocating piston, the interconnection means being normally held out of their

40 range.

As shown in Figs. 1 to 3 the cam disks 2 operate on respective antifriction rollers 3 mounted at the end of pivoted arms 4 carried by trunnions 5 on a plate 6 on the side 45 of the engine crank case or other suitable place. The pivoted levers 4 are made as long as possible so that no appreciative error is present by the passage of the roller center 3 through an arc instead of in a straight line passing through the center of the shaft 1.

50 At the other end of the pivoted levers 4 connection means are provided for the cords 7 or other means connected to the indicator 55 8 mounted in a plug on the cylinders 9, 10. It is obvious that in tandem engines such as

in the particular instance illustrated, a single pivoted lever 4 may operate indicators or a pair of cylinders 9, 10. Similarly, a single lifting disk can be used for more than one cylinder where the pistons of such cylinders are reciprocating in phase with one another. The cord 7 passes over a quadrant 11 mounted on a pivot 12 and from thence a further cord passes from quadrant 13 to a second indicator. If desired, the quadrants 11, 13, may be differential with respect to one another. By the use of such quadrants it is insured that the cord 7 is always moving at a speed which has a constant function of the speed of lift of the eccentricities 2.

The cords 7 are detachably connected to the ends of the lever 4 by means of rings on their ends engaging with hooks 14 adjustably secured at the end of the arms 4 by pins 15 passing through one of a number of perforations in the end of this arm.

The roller 3 of each arm 4 will normally be held firmly in contact with its cam disk 2 by means of a spring 16 connected to the arm 4 by means of a link 17. The roller 3 is normally held out of range of the lifting disk 2 by means of a catch 18 or any other equivalent device. It will be seen 85 therefore that by a simple releasing of the catch 18 it would be possible immediately to obtain an indicator diagram of the particular cylinder, the motion of the pistons of which corresponds with the motion of the cam of the release lever. If all the catches 18 are released simultaneously it is possible to simultaneously obtain diagrams for all the cylinders of the engine.

To restore the arm 4 to its inoperative position it is sufficient to depress the outer end until it comes into reach of the catch 18. In the case of a central lever or one similarly awkwardly placed, the lever may be provided with an operating handle 19.

100 Similarly, any connecting cord 7 can be detached from its hook 14 by drawing it down by means of a handle 20 upon it in the manner usual on indicating apparatus.

In high speed engines of course it would be desirable that the parts such as the lever 4, should be balanced about their pivotal points, such as 5.

110 To obtain extreme accuracy it would, of course, be desirable to connect the cord 7 to the end of the levers 4 by means of quadrants, but where the lever 4 is of consider-

able length relatively to the arc described by the ends of the lever during rotation of the crank shaft through one revolution, such refinement would not always be necessary.

- 5 In the modified arrangement shown in Fig. 4 the cam disks 2 act directly on spring controlled plungers 21 normally forced into contact with the surface of the lifting disks 2 by means of springs 22 and connect with 10 cord 23 passing to the indicator and moving over guide pulleys such as 24. In such an arrangement to hold the plunger 21 out of contact with the cam 2 during normal running of the engine, a catch or hook 25 may 15 be provided on a fixed part of the machine. Any other suitable arrangement for this purpose however may be used.

In the modified arrangement shown in Fig. 5 the plunger 21 is connected by a link 26 to 20 a quadrant 27 pivoted at 28 to a fixed part of the machine, such as the crank case, which quadrant is connected at one end 29 to the cord 30 of the indicator. By this means it is possible to obtain accurate rectilinear 25 placement of the cord 30 so that this is moving constantly with the velocity which is a constant function of the velocity of the piston, the movement of which it is reproducing.

30 An improved plug for the reception of an indicator to be mounted upon the cylinder of a fluid pressure engine is used which permits of communication being made at will between the interior of the cylinder and the 35 indicator without stopping the engine, and which can remain as a permanent fixture upon the engine.

The device consists of a plug 31 adapted to be permanently screwed into a hole in the 40 cylinder 32, or in the arrangement shown secured to the cylinder by means of a flange upon it and studs. The plug 31 is provided with a seating 33 which is closed by the 45 outer end 34 of a spindle 35 passing through the outer end of the plug 31 and having a portion 36 at its outer end in threaded engagement therewith. The spindle 35 passes down an axial hole 37 in the plug communicating with a side passage 38 having a 50 threaded end 39 to receive the indicator.

The spindle 36 can be moved axially along the passage 37 by turning it by means of the bolt head 40 so that the valve 34 leaves the seating 33 and permits of free passage between the passageway 38 and the interior 55 of the cylinder through the passage 37. A lock nut 41 is carried by the threaded end 36 of the spindle 35 to secure this in any desired position.

60 A bracket 42 is preferably mounted on the plug 31 and it may consist in a simple form of a piece of bent metal secured by the studs holding the plug 31 on to the cylinder 32 and having a portion 43 extending above the head 40 of the spindle 35 to firstly act as

an indicator for the position of the stud 40, and secondly, to prevent the stud 40 being withdrawn too far and so allow gases to blow right through the passage 37 into the open air.

70 A further passageway 44 communicates with the passage 37 leading to the atmosphere and closed by a one-way valve, such as a ball valve 47.

75 It will be seen that by means of this plug it is possible to obtain at any time while the engine is running without stopping the engine, an indicator diagram by simply turning the spindle 40 so that the part 34 leaves the valve seat 33. On the compression and 80 firing strokes of the engine the passage 37 of the plug 31 is filled with gas under pressure, but on the induction stroke of the engine, the valve 47 will automatically open 85 and air entering will clear all accumulations of gas burnt, unburnt, or burning, glowing particles or deposit from the passage 37, which is important to prevent premature ignition. If desired a cock 45 may be 90 mounted on the end of the passage 44, to isolate passage completely from atmosphere but the preferred arrangement will be that in which air is allowed to enter at certain times past the valve 47.

95 The permanent tightness of the valve 34 is insured as after the diagram has been made the spindle is returned upon its seat 33 and the valve faces 33, 34 are not subjected to constant corrosive action of gas or the like. Further no carbon deposit or the like will be formed on the valve faces or in the passage 37.

100 Further, as the plug 31 is detachable from the cylinder the seating 33 can be renewed at any time, in contradistinction to arrangements where the seating has been provided in the cylinder itself.

105 Further, it will be seen that while the plug is in position it is possible to remove the indicator screwed into the opening 39 and replace this by another, also adjustments and replacements can be made to the shifting valve 46, 47.

110 I declare that what I claim is:

115 1. An indicating arrangement for multiple cylinder fluid pressure reciprocating engines, having one or more pairs of pistons reciprocating in phase, comprising elements directly on and moving in phase with and common to said pairs of pistons, permanent driving connections between said elements and the crank shaft of said engine, one or more pairs of indicators mounted on respective cylinders adapted to be operated by said elements, and means to interrupt the connections between said indicators and said elements to leave the latter the sole constantly moving parts.

120 2. An indicating arrangement for fluid pressure engines, comprising a plug detach-

- ably mounted on the cylinder and adapted to carry the indicator, which plug has a passageway communicating with the indicator and with the interior of the cylinder, and a threaded spindle valve mounted axially along the passage, so that this may be closed to fluid from the cylinder during times when the indicator is not in use, a bracket on the plug and an arm extending therefrom adjacent the end of the spindle to serve as an indicator for the position of the threaded spindle valve, and as a means to prevent undue movement of the plug axially along the passage.
3. An indicating arrangement for fluid pressure engines, comprising a detachable plug having a passageway communicating with the cylinder on which the plug is adapted to be permanently secured, and having side passages communicating with said passageway, an indicator on one of said side passageway, an automatic one-way valve on the other side passage to place this in communication with the atmosphere during certain times such as during the suction stroke of the engine, to clear away products of combustion and prevent premature ignition, a valve controlling the main passageway having the two side passages, and a hand-controlled cock controlling communication from the atmosphere to the outside of said automatic valve.
4. An indicating arrangement for fluid pressure reciprocating engines comprising a continuously rotating spindle, eccentric disks on said spindle, reciprocating in phase with each reciprocating piston, an indicator device operated by said eccentrics mounted on each cylinder, and means to interrupt the connection between the indicator and the eccentric disks, leaving these eccentric disks the only part of the indicator on the engine which is moving.
5. An indicating arrangement for fluid pressure reciprocating engines, comprising a spindle rotating in phase with the main shaft of the engine, eccentric disks mounted on said spindle, reciprocating fingers mounted on the engine, a quadrant connected to each reciprocating finger, a cord connecting said quadrant and said indicator device, means to hold the finger in contact with the said eccentric disks, and a catch to lock the fingers out of range of the eccentric disks, thereby interrupting the connection between the indicator and the eccentric disk, leaving this latter part on the engine alone moving.
6. An indicating arrangement for fluid pressure engines, comprising a plug, de-
- tachably mounted on the cylinder and adapted to carry the indicator, a valve closing a passage-way in said plug communicating with the indicator and preserving with the lower face of the plug a surface of the cylinder whereby the compression value in the cylinder is maintained constant whether the plug is mounted on the engine or not.
7. An indicating arrangement for fluid pressure engines comprising a plug detachably mounted on the cylinder, adapted to carry the indicator, having a passageway in it connecting the cylinder with the indicator, and a valve controlling said passageway but adapted to present with the remaining portion of the plug when in position on the cylinder, a surface flush with the normal internal surface of the cylinder whereby the compression value in the cylinder remains at its predetermined value during those times when the indicator is not in use.
8. An indicating arrangement for fluid pressure engines comprising a plug detachably mounted on the cylinder, adapted to carry the indicator, having a passageway in it connecting the cylinder with the indicator, and a threaded spindle valve receding along its end axis controlling said passageway but adapted to present with the remaining portion of the plug when in position on the cylinder, a surface flush with the normal internal surface of the cylinder, whereby the compression value in the cylinder remains at its predetermined value during those times when the indicator is not in use.
9. An indicating arrangement for fluid pressure engines, comprising a plug detachably mounted on the cylinder, adapted to carry the indicator, having a passageway in it connecting the cylinder with the indicator, a threaded spindle valve opening inward away from the cylinder, controlling said passage-way but adapted to present with the remaining portion of the plugs when in position on the cylinder a surface flush with the normal internal surface of the cylinder, whereby the compression value in the cylinder remains at its predetermined value during those times when the indicator is not in use.

In witness whereof, I have hereunto signed my name this 19th day of April 1917, in the presence of two subscribing witnesses.

ARTHUR RYDER.
